UNITED STATES PATENT OFFICE

132,041

DESIGN FOR A TURBOGENERATOR UNIT

Donald L. Hadley, Wilkinsburg, Pa., assignor to
Westinghouse Electric & Manufacturing Com-
pany, a corporation of Pennsylvania

Application February 3, 1942, Serial No. 105,607

Term of patent 7 years

To all whom it may concern:

Be it known that I, Donald L. Hadley, a citizen of the United States, residing at Wilkinsburg, in the county of Allegheny and State of Pennsylvania, have invented a new, original, and ornamental Design for a Turbo-Generator Unit, of which the following is a specification, reference being had to the accompanying drawing, forming a part thereof.

Fig. 1 is a side perspective view of a turbo-

generator unit with the generator end at the front showing my new design; and

Fig. 2 is an opposite side perspective view of the same unit viewed from the turbine end.

I claim:

The ornamental design for a turbo-generator unit, substantially as shown.

DONALD L. HADLEY.
